(57) **CLAIM**

What is claimed is the ornamental design for a film roll with edge protectors, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective of a first embodiment of a film roll with edge protectors, showing our new design with red edge protectors;

FIG. 2 is front view thereof;

FIG. 3 is a right side view thereof;

FIG. 4 is a top view thereof;

FIG. 5 is a rear view thereof;

FIG. 6 is a left side view thereof;

FIG. 7 is a bottom view thereof;

FIG. 8 is a perspective of a second embodiment of a film roll with edge protectors, shown with orange edge protectors;

FIG. 9 is a front view thereof, the rear view, right side view, and left side view being the same as the front view;

FIG. 10 is a top view thereof, the bottom view being the same as the top view;

FIG. 11 is a perspective of a third embodiment of a film roll with edge protectors, shown with yellow edge protectors;

FIG. 12 is a front view thereof, the rear view, right side view, and left side view being the same as the front view;

FIG. 13 is a top view thereof, the bottom view being the same as the top view;

FIG. 14 is a perspective of a fourth embodiment of a film roll with edge protectors, shown with green edge protectors;

FIG. 15 is a front view thereof, the rear view, right side view, and left side view being the same as the front view;

FIG. 16 is a top view thereof, the bottom view being the same as the top view;

FIG. 17 is a perspective of a fifth embodiment of a film roll with edge protectors, shown with blue edge protectors;

FIG. 18 is a front view thereof, the rear view, right side view, and left side view being the same as the front view;

(Continued)

FIG. 19 is a top view thereof, the bottom view being the same as the top view;
 FIG. 20 is a perspective of a sixth embodiment of a film roll with edge protectors, shown with purple edge protectors;
 FIG. 21 is a front view thereof, the rear view, right side view, and left side view being the same as the front view;
 FIG. 22 is a top view thereof, the bottom view being the same as the top view;
 FIG. 23 is a perspective of a seventh embodiment of a film roll with edge protectors, shown with black edge protectors;
 FIG. 24 is a front view thereof, the rear view, right side view, and left side view being the same as the front view;
 FIG. 25 is a top view thereof, the bottom view being the same as the top view;
 FIG. 26 is a perspective of an eighth embodiment of a film roll with edge protectors, shown with white edge protectors;
 FIG. 27 is a front view thereof, the rear view, right side view, and left side view being the same as the front view;
 FIG. 28 is a top view thereof, the bottom view being the same as the top view;
 FIG. 29 is a perspective of a ninth embodiment of a film roll with edge protectors, wherein differing stippling on upper and lower edge protectors represents that the upper and lower edge protectors have a contrast in appearance;
 FIG. 30 is a front view thereof, the rear view, right side view, and left side view being the same as the front view;
 FIG. 31 is a top view thereof;
 FIG. 32 is a bottom view thereof;
 FIG. 33 is a perspective of a tenth embodiment of a film roll with edge protectors;
 FIG. 34 is front view thereof;
 FIG. 35 is a right side view thereof;
 FIG. 36 is a top view thereof;
 FIG. 37 is a rear view thereof;
 FIG. 38 is a left side view thereof;
 FIG. 39 is a bottom view thereof;
 FIG. 40 is a perspective of an eleventh embodiment of a film roll with edge protectors;
 FIG. 41 is front view thereof;
 FIG. 42 is a right side view thereof;
 FIG. 43 is a top view thereof;
 FIG. 44 is a rear view thereof;
 FIG. 45 is a left side view thereof; and,
 FIG. 46 is a bottom view thereof.
